UNITED STATES PATENT OFFICE.

LOUIS SEVERUS, OF CHICAGO, ILLINOIS, ASSIGNOR TO THE ART LAMP MFG. COMPANY, A CORPORATION OF ILLINOIS.

DESIGN FOR A LAMP BRACKET.

Application filed October 15, 1923. Serial No. 7,497. Term of patent 3½ years.

To all whom it may concern:

Be it known that I, LOUIS SEVERUS, a citizen of the United States, residing at Chicago, in the county of Cook and State of Illinois, have invented a new, original, and ornamental Design for a Lamp Bracket, of which the following is a specification, reference being had to the accompanying drawings, forming part thereof.

The figure is a front elevation of the new and original lamp bracket.

I claim:

The ornamental design for a lamp bracket as shown.

LOUIS SEVERUS.
